UNITED STATES PATENT OFFICE.

GEORGE ELLIS ROBINSON, OF PORTLAND, OREGON.

ENGINE-LATHE ATTACHMENT.

1,306,720.

Specification of Letters Patent. Patented June 17, 1919.

Application filed August 27, 1918. Serial No. 251,651.

To all whom it may concern:

Be it known that I, GEORGE E. ROBINSON, a citizen of the United States, and a resident of Portland, in the county of Multnomah and State of Oregon, have invented certain new and useful Improvements in Engine-Lathe Attachments, of which the following is a specification.

My invention is an improvement in engine 10 lathe attachments, and has for its object to provide an attachment of the character specified especially adapted for grinding, regrinding and boring engine cylinders, and which may be adjusted to grind cylinders 15 of different diameters.

In the drawings:

Figure 1 is a perspective view of the improvement in use;

Fig. 2 is an end view of the attachment 20 removed;

Fig. 3 is a longitudinal vertical section through the attachment;

Figs. 4 and 5 are sections on the lines 4—4 and 5—5, respectively, of Fig. 3;

Fig. 6 is a side view of the conical bearing sleeve for the grinding shaft;

Fig. 7 is a section on the line 7—7 of Fig. 6.

In the present embodiment of the invention, the attachment comprises a shaft 1 which has secured to one end thereof a grinding wheel 2, and the shaft is journaled within a casing or sleeve 3. This sleeve at the end remote from the grinding wheel has 35 threaded engagement with a hub 4 on an offset plate 5, which is adjustably connected with a base plate 6 in a manner to be presently described.

The offset plate and the base plate are 40 recessed on their adjacent faces, as shown at 7 and 8, respectively, and the end of the shaft 1 extends into the recess 7, a shaft 9 which is a part of the lathe extending into the recess 8, and when the parts are in normal 45 position the shafts 1 and 9 are in alignment. Each shaft 1 and 9 has a sprocket wheel 10 and 11, respectively, secured to the inner end thereof, and these sprocket wheels are connected by sprocket chains 12 50 with sprocket wheels 13 and 14 secured to a stub shaft 15 which is connected with both plates 5 and 6. Referring to Fig. 3, it will be noted that the pinions 13 and 14 which are integral are mounted upon an eccentric 55 16 rigid with the stub shaft 15, a bushing being arranged between the sprocket wheels

and the eccentric, and this shaft 15 is capable of being rotated with respect to the plates 5 and 6, to vary the eccentricity of the eccentric 16, to provide a means of tightening 60 the sprocket chains 12.

The plate 5 is adjusted with respect to the plate 6 by means of a micrometer adjustment, the said adjustment consisting of a threaded rod 18 which is journaled in a bearing 19 on the plate 6 and has engagement with a nut 20 in the head of a bolt which passes through one of a series of openings 21 in the plate 5 and through an arc shaped slot 22 in the plate 6, and is engaged by the rod on the opposite face of the plate 6 from the plate 5.

This rod has a handle 23 at its upper end and a scale, as shown in Fig. 2, is provided in connection with the rod for indicating 75 the degree of variation between the axes of the shafts 1 and 9.

The plate 6 has a hub portion 24 which, as shown in Fig. 3, is adapted to engage the face plate 25 of the lathe indicated at 26, 80 and to be secured to the face plate by means of screws 27, as shown. When so connected, it will be obvious that by means of the micrometer screw adjustment the plates 5 and 6 may be moved with respect to each other, 85 to cause the shaft 1 to take a position eccentric to the shaft 9, so that the said shaft 1 will not only be rotated on its own axis through the sprocket wheels 10, 11, 13 and 14 and the chains 12, but it will also be given 90 a bodily movement of revolution around its axis, through the rotation of the plates 5 and 6. Thus the cylinders 28 may be exactly ground, reground or bored.

The projector or casing 3 has radial openings 29 near the plate 5 for engagement by a spanner, to turn the said casing when it is desired. The said casing has a spiral groove 30 on its periphery, extending from one of these recesses to the opposite end, and delivering at the bearing for the shaft 1 at this end, and within the groove is arranged a tube 31 for carrying a lubricant.

A bushing 32 is arranged between the inner end of the shaft 1, the hub of the offset plate and the tubular casing, as shown in Fig. 3, and the shaft 1 has a collar 33 at the outer end of the bushing. Another collar 34 is provided near the outer end of the shaft, and a washer 35 is arranged adjacent 110 to the collar and on the outer side thereof.

It will be noticed that the bore of the

tubular casing 33 adjacent to the grinding wheel is flaring and a frusto-conical bushing 36 is arranged in this flaring portion at the outer side of the washer 35. This bushing, 5 as shown more particularly in Figs. 6 and 7, is provided with two series of longitudinally extending splits, the members of one series extending from one end and the members of the other series from the other end, and 10 the members of the series alternate, as shown. Thus a resilient bushing is provided.

A washer 37 is arranged at the outer large end of the bushing, and a dust cap 38 is 15 threaded on to the casing outside of the washer. A lubricating chamber is provided in the dust cap, at the outer end of the tubular casing, and the groove 30 has a passage 39 extending into this chamber. Referring 20 to Fig. 3 it will be noticed that the shaft 1 is sectional, the two sections having an interlocking tongue and groove connection adjacent to the collar 33.

A shaft 9 extends through the head stock 25 of the lathe and has a small pulley attached to the end, which in turn is connected by a belt to the countershaft extending above the lathe. The surplus oil accumulating in the dust cap 38 is carried away by a second 30 spiral tube 30.

I claim:

1. A lathe attachment comprising a grinding shaft having at one end an offset plate in which the grinding shaft is journaled, a 35 base plate having means for connecting the same with the face plate of the lathe, the

offset plate and the base plate being pivoted eccentric to the grinding shaft and the axis of rotation of the base plate, a micrometer screw adjustment at the other end of the 40 said plates for moving the offset plate with respect to the base plate, rigidly connected sprocket wheels at the pivotal connection of the plates, a sprocket wheel on the grinding shaft, a sprocket wheel at the axis of rotation of the base plate, chains connecting the respective wheels, an eccentric mounting for the rigidly connected sprocket wheels and adjustable for tensioning the chains, said 45 offset plate and base plate being recessed on their adjacent faces to receive the wheels and chains and to form a housing for the said wheels and chains.

2. A lathe attachment comprising a grinding shaft having at one end an offset plate 55 in which the grinding shaft is journaled, a base plate having means for connecting the same with the face plate of the lathe, the offset plate and the base plate being pivoted eccentric to the grinding shaft and the axis 60 of rotation of the base plate, a micrometer screw adjustment at the other end of the said plates for moving the offset plate with respect to the base plate, rigidly connected sprocket wheels at the pivotal connection of 65 the plates, a contact wheel on the grinding shaft, a sprocket wheel at the axis of rotation of the base plate, chains connecting the respective wheels, an eccentric mounting for the rigidly connected sprocket wheels and 70 adjustable for tensioning the chains.

GEORGE ELLIS ROBINSON.
